UNITED STATES PATENT OFFICE.

ATHELSTAN H. CHRISTIE, OF ST. LOUIS, MISSOURI.

HANDBAG.

1,399,377.

Specification of Letters Patent.

Patented Dec. 6, 1921.

Application filed April 23, 1921. Serial No. 463,747.

To all whom it may concern:

Be it known that I, ATHELSTAN H. CHRISTIE, a citizen of the United States, and resident of the city of St. Louis and State of Missouri, have invented certain new and useful Improvements in Handbags, of which the following is a specification containing a full, clear, and exact description, reference being had to the accompanying drawings, forming a part hereof.

My invention relates to improvements in hand bags and has for its primary object a hand bag of the Gladstone type which is equipped along its outside edges with a reinforcing strip of wear resisting material.

A further object is to construct a hand bag having along its outside edges a strip of wear resisting material to which the sides and gussets are attached.

In the drawings,

Figure 1 is a perspective view of a hand bag embodying my improvement.

Fig. 2 is an enlarged fragmental perspective section of a portion of the hand bag showing my improved reinforcement.

In the construction of my device I employ a hand bag having a hinged frame 3 which is of the usual construction. To this frame are attached gussets 4 and 5. These gussets being of flexible leather. The sides 6 of the bag are constructed of relatively stiff material and are provided along their edges with a reinforcement 7. Interposed between the sides 6 and the gussets 4 and 5 is a reinforcing strip which is formed preferably of sole leather, raw hide or the like. This strip consists of the half round portion 8 and the projection 9, thus virtually making the reinforcing strip T-shaped in cross section. This reinforcing strip extends entirely around the edges of the side members as shown in Fig. 1, and in stitching the sides 6 and the gussets 4 and 5 to-

gether, the stitches 10 not only pass through the gussets, sides and reinforcing strip 7, 45 but also through the extending portion 9 of the reinforcing strip. When the bag has thus been assembled, the half round portion 8 is either left in this unfinished state, that is, just as it comes from the machine or it 50 may be dyed and varnished, so as to present a polished appearance. The purpose of this strip is not only to assist in stiffening the side edges of the bag, but also to protect the gussets when the bag is set on the floor. 55 By making this strip of leather or raw hide, a certain amount of flexibility is given to the edges and no reinforcing corners or wire frames are necessary to hold the bag in shape.

Having fully described my invention, what I claim is:

1. A hand bag comprising a pair of relatively stiff sides, a T-shaped reinforcing strip formed of sole leather and provided 65 with a rounded exterior edge extending around the edges of said sides and being substantially flush with the sides, a gusset, a row of stitching passing through the sides and gussets and reinforcing strip for uniting 70 the same together, and a hinged frame to which said gussets are attached.

2. A hand bag comprising relatively stiff sides, gussets for said sides, a reinforcing strip formed of sole leather and provided on 75 opposite sides with channels for receiving and protecting the adjacent edges of the sides and gussets, said reinforcing strip having a rounded exposed head projecting over the edges of the sides and gussets, and a 80 row of stitching passing through the sides, reinforcing strip, and gussets for uniting the same together.

In testimony whereof I have signed my name to this specification.

ATHELSTAN H. CHRISTIE.
